UNITED STATES PATENT OFFICE.

OSCAR MARTIN CARTER, OF HOUSTON, TEXAS.

EXPANSIVE AND CONTRACTIVE DEEP-WELL DRILL.

Application filed July 8, 1922. Serial No. 573,153.

This invention relates to expansive and contractive deep well drills especially adapted for use in drilling oil and other wells and is an improvement on the construction illustrated in my United States Patent No. 1,412,101 issued April 11, 1922 and my other patents in this art.

Briefly stated, this invention aims to provide a deep well expansive and contractive drill having simple means whereby the cutters or bits are automatically moved to their operative positions with relation to the drill stem when the same reach the limit of their downward movement.

15 Further the invention forming the subject matter of this application aims to provide novel means whereby the pressure on the bits is absolutely prevented from collapsing the bits, the said means being in the nature of a plurality of locking devices, all of which are more or less independent of each other and which mutually contribute to successfully hold the bits in their operative positions.

25 A further object is to provide a novel means whereby excessive friction on the downward or upward movement of the underreamer is prevented and the invention is also provided with simple means whereby the lowering cable is prevented from being prematurely released.

A further aim is to provide an expansive and contractive drill having a plurality of ball and socket joints which enable the drill 30 to conform to longitudinal bends in the drill stem.

An equally important object of this invention is to provide simple means whereby the bits are securely though detachably connected to the bit holder in such a manner that the same may be quickly detached when the drill is brought to the surface for the renewal of the bits.

Other objects and advantages of the invention will be apparent during the course 45 of the following description.

In the accompanying drawings, forming a part of this application and in which like numerals are employed to designate like 50 parts throughout the same,

Figure 1 is a side elevation of the drill within a drill stem, the same being shown in the position it occupies during the removal thereof, and parts being shown in 55 section.

Figure 2 is a vertical detail sectional view

through the drill, the same being shown within the lower portion of the drill stem collar.

Figure 3 is a detail sectional view illustrating the drill stem collar and the specific means employed for guiding the bit holders into locking engagement with the lower portion of the collar. 60

Figures 4 and 5 are side elevations of the improved drill completely collapsed, parts of the drill being shown in section. 65

Figures 6 and 7 are side elevations illustrating the position assumed by the various parts of the drill during its descent through 70 the casing, the carrier of the drill being shown partly in section.

Figures 8 and 9 are elevations of the improved drill, the parts being shown in their operative positions ready for the drilling operation, the bit carrier being shown partly 75 in section.

Figure 10 is an elevation of one of the locking pawls, the same being employed for locking the bit operating rack to the bit carrier, whereby to prevent collapse of the bits as the result of end pressure thereon. 80

Figure 11 is an edge elevation of the locking pawl illustrated in Figure 10, one of which is located on each side of the rack. 85

Figure 12 is an end elevation illustrating the lower end of the bit carrier, parts of the same being beveled for the passage of mud pumped down through the drill stem during 90 drilling operation.

Figure 13 is a fragmentary side elevation illustrating the means for connecting the drill to the lowering cable or member, the view also illustrating the means for releasing the lowering cable or member when the drill has reached the limit of its downward movement within the drill stem. 95

Figure 14 is a fragmentary perspective illustrating the means for connecting the drill to the lowering cable. 100

Figure 15 is a fragmentary perspective of a pair of sectional weights embodied in the invention, which sectional weights act to move the bits to their operative positions. 105

Figure 16 is an elevation of one of the bit holders, the bit carried thereby, and an operating link connected to the bit.

Figure 17 is a side elevation of the bit holder, the view being taken from the opposite side from that illustrated in Figure 16. 110

Figure 18 is a side elevation of a rack embodied in the invention.

Figure 19 is an edge elevation of the rack illustrated in Figure 18, the same being connected to the bit holders for moving the same to their operative and inoperative positions.

Figure 20 is an edge elevation of the main portion of the controlling bar or mandrel embodied in the invention.

Figure 21 is a side elevation of the same, 10 Figure 22 is a side elevation of the bit carrier.

Figure 23 is a side elevation of the drill stem collar and the lower portion of the drill extended through the collar, parts being 15 shown in section.

In the drawing wherein for the purpose of illustration is shown a preferred embodiment of the invention, the numeral 5 designates a tubular carrier the forward portion 20 of which pivotally supports a pair of bit holders 6 through the medium of pivot pins 7. Figure 22 illustrates that the forward portion of the carrier 5 is provided with oppositely arranged slots 8 through which the 25 bit holders pass when the same are extended to the positions illustrated in Figure 9.

With reference to Figures 9, 16 and 17 it will be observed that a bit 9 is detachably connected to each bit holder through the medium of a fastening bolt or member 10 and one side of the bit holder is undercut to provide a beveled shoulder 11 which securely and positively prevents movement of the bit with relation to the holder and also reduces 35 the number of necessary fastening devices 10 to one. The bit 9 has one edge beveled for engagement with the undercut edge 11 of the holder and the bit is thereby securely and positively held in position. The bit 9 extends for a slight distance beyond the forward end of the holder and is provided with beveled edges for engagement with the bottom of the well.

The rear ends of the bit holders 6 are provided with curved shanks 13 to which operating links 14 are pivotally connected as indicated at 15 and by reference to Figure 16 it will be observed that the forward portion of the link 14 is cut away so that the same may overlap the shank 13 in the manner illustrated in Figure 17. The link 14 is shown in Figure 17 in the position it occupies when the bits are fully extended and the link is provided with a transverse groove 16 which registers with a groove or socket 17 in the bit holder for the reception of the tapered forward end 18 of the main controlling bar 19 which as illustrated in Figures 5, 7 and 9 passes centrally through the bit carrier 5. When the controlling bar 19 is advanced the forward end 18 of the same is received within the grooves 16 and 17 so as to lock the bits, of which there are two, in the operative position as illustrated in Fig. 65 9. It is thus seen that when the forward end

18 is received within the grooves 16 and 17 the bit holders are positively prevented from collapsing as a result of pressure thereon.

Figures 5, 7 and 9 illustrate that the rear 70 ends of the links 14 are pivoted to racks 20 movable longitudinally within the carrier 5 and connected by cross bars 21, 22 and 23.

The main controlling bar 19 is extended a substantial distance above the carrier 5 75 and forms a supporting means for the drill and when it is desired to collapse the bit as illustrated in Figures 5 and 7, the controlling bar 19 is moved upwardly so that the oppositely arranged projections 24 on the same will be engaged with the cross members 22 of which there are two, and this will move the racks upwardly. Also the mandrel or controlling bar 19 is provided in its forward portion with a longitudinal slot 25 for the reception of a stop pin 26 carried by a cross bar 27 rigidly secured to the carrier. When the supporting means (to be later described) is engaged with the operating or controlling bar 19 and the bit is lowered into the well 90 the stop pin will be engaged with the bottom portion of the slot 25 and the weight of the racks 20 will cause the bit holders 6 to expand to the position illustrated in Figure 7. However, as the bit descends into the well and reaches an enlarged part of the drill stem to be later described the bit holders will be free to move outwardly and consequently the racks 20 will descend further or move downwardly with relation to the main 100 controlling bar 19.

When the racks 20 are thus moved downwardly with relation to the controlling bar a projection 30 formed on one of the racks will engage a holding dog 32 and swing the same laterally on the stop pin 26. That is to say the holding dog 32 is pivoted to the stop pin 26 and when the rack 30 descends the upper portion of the dog will be moved laterally from beneath a lug 31 on the controlling bar 19. This releases the main controlling bar and permits the same to descend. Figure 7 illustrates that when the bit holders are partly open a lug or actuating member 33 on the cross bar 21 engages a shoulder 34 on the intermediate portion of the dog and thereby holds the dog in a set position. However, the holding lug 33 advances with the rack 20 and thereby releases the dog 32 for movement to the right. 115

As the racks 20 advance the main controlling bar 19 will partake of a similar movement and the projections 24 will engage the upwardly directed terminal portions 35 of a pair of oppositely arranged locking pawls 36 and swing the locking pawls on their pivots and into openings or notches 37 in opposite sides of the carrier. 125

Figure 9 plainly illustrates one of the pawls 36 within the notch 37 so as to posi- 130

tively prevent the rearward movement of the rack 20 and the premature collapse of the bit as the result of excessive pressure thereon.

5 However, when it is desired to collapse the bits, for removal of the drill the controlling bar 19 is drawn upwardly by means to be later described and the lug 31 will be moved out of the way of the dog 32 while 10 the projections 24 will be moved out of locking engagement with the pawls 36. Now as the controlling bar 19 moves upwardly the upper ends of the projections 24 will be engaged with the cross bars 22 so as to retract 15 the rack. The upward movement of the rack will cause the lug 33 to engage the shoulder 34 on the dog 32 and consequently return the dog to its original position as illustrated in Figure 7 so that the controlling 20 bar cannot descend.

It will be noted that when the parts are in their lowering position as illustrated in Figure 7 the weight of the controlling bar and the members mounted thereon is transmitted to the carrier through the lug 31 the dog 32 and the cross member 27 which is rigidly connected to the carrier.

The improved drill is lowered through a drill stem 40, the lower end of which is provided with a drill stem collar 41 having oppositely arranged cavities or slots 42 for the passage of the bits and bit holders. The drawings illustrate that the collar 41 is greater in internal diameter than the internal diameter of the drill stem and consequently when the bits enter the collar 41 they may expand slightly which will result in the downward movement of the racks. Figure 3 illustrates that the interior of the 40 collar 41 is provided with oppositely arranged grooves 43 which gradually decrease in width toward their lower ends so as to guide the bit holders into the slots. The grooves 43 not only serve as a means for 45 guiding the bit holders into the slots 42 but also as a very effective means for causing the notches 44 on the lower end of the carrier to receive supporting lugs or pins 45 extending inwardly from opposite sides of 50 the collar 40. This prevents the bit from moving out of the lower end of the collar or drill stem during the drilling operation.

Attention is directed to the fact that that portion of the collar directly behind each 55 bit holder is formed with an extension which effectively braces the bit holder and reduces the strain on the same to a minimum. That is to say the drill stem collar is provided on opposite sides with depending portions 60 which contact with the adjacent bit holders and thereby brace the same.

As previously stated, the upper portion of the controlling bar 19 is extended a substantial distance upwardly of the carrier and the 65 rack and a plurality of sectional weights are

mounted thereon, the said sectional weights being designated by the numerals 50 and 51. In carrying out the invention the sectional weights 50 and 51 are mounted for sliding movement on the controlling bar and the 70 weights may move upwardly but not downwardly with relation to the controlling bar. Figure 23 illustrates that the controlling bar is formed with an annular shoulder 53 which contacts with an internal shoulder 54 on the 75 sectional weight 50 and below a collar 53^a on the controlling bar which engages shoulder 54 and thereby prevents the sectional weights from moving downwardly with relation to the controlling bar. Sectional weight 51 is 80 similarly held against downward movement relative to the controlling bar by a collar 51^a on said bar similar to collar 53^a. However, when the dog 32 is moved to the position illustrated in Figure 9 the mandrel or controlling bar will descend and the sectional weights will also descend for engagement with the rack and thereby force the bits to their operative positions.

Figure 14 illustrates that the upper portion of the controlling bar 19 is connected through the medium of a rivet 55 with a pair of ears 151 to which the shanks 153 of gripping jaws 54' are pivoted, as indicated.

Jaws 54' have their opposed sides formed with recesses for the reception of the flattened and flared forward end 57 of a lowering member 58. The shanks 153 are urged outwardly by means of coiled springs 59 confined between the shanks and a tubular extension 60 depending from the head 51.

The inwardly extending terminal portions 61 of the shanks 153 may be positively held in the position illustrated in Figure 13 by means of the annular rib 63 formed on the upper end of a sliding collar 64. The annular rib 63 forms one side of an annular groove 65 which is adapted to receive the inwardly extending terminal portions 61 of the shanks 153. When the inwardly extending terminal portions 61 are received within or are arranged opposite the annular groove 65 the connection between the jaws 54' and the lowering member 58 may be broken so as to release the lowering mechanism for withdrawal to the surface.

The collar or head 64 is provided with a pair of depending stems or actuating rods 68 which are received in oppositely arranged grooves in opposite sides of the upper sectional weight 51 and as illustrated in Figure 15 the depending stems 68 terminate slightly in advance of the upper weight 51 for engagement with the upper end of the lower weight 50.

When the controlling member 19 descends to the position illustrated in Figure 9 as a result of its release, the sectional weights also descend and as the foremost sectional weight 50 is limited in its descent by en-

gagement with the racks the upper end of the lower sectional weight will be engaged with the lower end of the depending stems 68 whereupon the annular groove 65 will be positioned between the inwardly extending terminal portions 61 of the shanks 153.

A slight pull on the cable or lowering member 58 will result in the disconnection of the same from the jaws 54'.

- 10 The drill in its descent through the drill stem encounters extremely heavy mud and the pressure of this mud on the sectional weight is prevented from moving the weight upwardly by means of a spring locking arm 80, the terminal portion of which is formed with a hook received in a longitudinally extending socket or recess 81 in the lower end of the lower weight 50. With reference to Figure 7 it will be observed that the hooked end portion of the arm 80 will positively prevent the lower sectional weight from prematurely actuating the depending stems 68 and the head 64.
- 15 20

In operation the drill is stood upright on the derrick floor and the head or collar 64 is moved to the position illustrated in Figure 8 so that the inwardly directed terminal portions 61 of the shanks 153 may move inwardly. This permits the lowering rod 58 to be positioned between and to be engaged by the jaws 54'. Now the shanks 153 are released by the fingers of the operator so that the springs 59 will move the same to the position illustrated in Figure 13. Subsequent to this the member 64 is lowered so that the rib 63 will be positioned between the inwardly directed terminal portions of the shanks 61 for positively holding the jaws in engagement with the lowering mechanism.

The bits being collapsed, the drill is introduced into the drill stem and the weight of the rack will cause the bits to move to the position illustrated in Figure 7 and contact with the interior of the drill stem. When the bits or cutters reach the enlarged collar 41 at the lower end of the drill stem they will move outwardly under the weight of the racks 20 and consequently the projections 30 will engage the rounded upper end of the dog 32. Simultaneously with the advance of the projections 30 the holding member 33 will be released from engagement with the shoulder 34 and the dog is thereupon swung to the right or to the position illustrated in Figure 9. This allows the mandrel and the weights carried thereby to descend.

60 When the mandrel or controlling bar 19 and sectional weights thus descend the reduced lower end 18 of the mandrel will be received within the grooves 16 and 17 so as to positively lock the bits in their extended positions. As previously stated the descent of the mandrel will force the locking pawls

36 to partake of a swinging movement, whereupon the same are received within the openings 37 for locking the racks to the carrier and preventing the collapse of the cutters as the result of side or end pressure 70 thereon.

When the controlling bar descends the sectional weight 50 will contact with the racks and of course move the cutters to their fully extended positions.

When the parts of the drill move to their operative positions illustrated in Figure 9 the upper end of the weight 50 will be engaged with the lower ends of the depending stems 68 so as to move the head 64 upwardly and consequently position the annular groove 65 between the inwardly directed terminal portions 61. By a slight sudden pull on the lowering member 58 the jaws 54' will be separated for releasing the lowering member. When the lowering member is released the driller will be accurately advised of the fact that the drill is in its fully extended position and all the locks are set. The drill stem may now be operated for continuation of drilling.

When it is desired to withdraw the drill for the purpose of renewing or sharpening the bits a raising device or lifting tongs 90 is sent down through the drill stem which engages with the cone-shaped head formed by the jaws 54' and the tongs 90 are subsequently moved upwardly so as to exert an upward pull on the controlling bar 19.

When an upward pull is exerted on the controlling bar 19 the sectional weights are drawn upwardly and the upper ends of the projections 24 are engaged with the cross bars 22 so as to move the racks upwardly and thereby collapse the bits. The extent of collapse of the bits is controlled by the length of the slot 25 and the engagement of the pin 26 with the lower end of the slot. When the pin 26 is engaged with the slot 25 due to the upward movement of the controlling bar 19 the carrier 5 then begins to move upwardly.

Moreover, as the racks begin their upward movement the lug 31 moves to the position illustrated in Figure 7 and the lugs 30 and 33 also move to the positions illustrated in Figure 7. With the parts thus positioned the weight of the controlling bar and sectional weights is removed from the racks but the racks still have a tendency to descend of their own weight and thus preserve the tendency of the cutters to expand whenever they enter the larger diameter of the collar at bottom of drill stem. The racks always press on the bit holders and tend to expand them which is a very important part of the invention.

As the well deepens, the mud within the drill stem is compressed near the bottom and becomes more dense and decreases the speed

75

115

120

125

130

with which the drill descends. The provision of the sectional weights successfully counteracts the density of the mud and causes the drill to move promptly to the 5 lower end of the drill stem and fully expand.

As the drill stem is sometimes curved, I have provided a plurality of universal joints 89 of any desired construction in the 10 controlling bar so that the drill may adjust itself to the bends in the stem.

Any desired number of weights and universal joints may be employed.

In carrying out the invention the upper 15 sectional weight 51 is provided with a plurality of longitudinally extending guide ribs 93 which center the drill in the stem and thereby facilitate the engagement of the raising tongs with the cone-shaped head.

20 As illustrated in Figure 12 the forward end of the bit carrier is provided with beveled faces 103 which cooperate with the beveled portions 104 of the bit holders in the formation of orifices thru which the mud 25 pumped down thru the stem passes. The orifices thus formed when the bit holders are expanded are so shaped that the mud as it is pumped down thru the drill stem is directed by each orifice along the front of 30 the opposite collar holder and thus keep the cutter holders and cutters clean so that they will drill better and also permit them to collapse easily where it is desired to withdraw the bit. In other words, each 35 recess 104 forms with the adjacent bevelled portion 103, a groove which simply guides the pumped mud across the front face of the opposite cutter holder.

More specifically one side of each cutter 40 is beveled as indicated at 104 and the adjacent side of the carrier is beveled as indicated at 103 so as to define a pocket through which the mud flows on its way to the bit. Of course there are two such 45 passages because each bit holder is provided with a beveled portion 104 and there are a corresponding number of beveled portions 103.

It is to be understood that the form of the 50 invention herewith shown and described is to be taken as a preferred example of the same and that such minor changes in arrangement and construction of parts may be made as will remain within the spirit of the 55 invention and the scope of what is claimed.

Having thus described the invention, what I claim is:—

1. An improved deep well expansive and contractive drill comprising a carrier, cutters pivoted thereto, racks for operating said cutters and a controlling bar movable through said carrier, said bar being normally supported by said racks and having means movable into engagement with the

cutters to lock the latter in operative position. 65

2. An improved expansive and contractive deep well drill comprising a carrier, cutters pivoted thereto, racks for operating said cutters and movable through said carrier, a 70 controlling bar having means to lock the cutters in operative position, and a locking pawl pivoted to one of said racks and adapted for locking engagement with said carrier, whereby to hold the racks in a set position. 75

3. An improved expansive and contractive deep well drill comprising a carrier, cutters pivoted thereto, racks for operating said cutters, a controlling bar movable through said carrier and having means to lock the cutters 80 in operative positions, locking pawls pivoted to said racks and adapted for locking engagement with said carrier, and means slidable on said controlling bar for advancing said racks and moving said cutters outwardly. 85

4. An improved expansive and contractive deep well drill comprising a carrier, cutters pivoted thereto, racks having connection with said cutters, a controlling bar movable 90 through said carrier and having a shoulder, a cross bar connected to said racks and arranged in the path of travel of said shoulder, and locking pawls pivoted to said racks and arranged in the path of travel of said 95 shoulder and operated thereby, said locking pawls being adapted for locking engagement with the carrier.

5. An improved expansive and contractive deep well drill comprising a carrier, cutters 100 pivoted thereto, racks having connection with said cutters, a controlling bar movable through said carrier and having a shoulder, a cross bar connected to said racks and arranged in the path of travel of said shoulder, locking pawls pivoted to said racks and arranged in the path of travel of said shoulders and operated thereby, a holding dog 105 pivotally supported by said carrier, and a lug carried by said controlling bar and engaged with said dog whereby the weight of said controlling bar is transmitted directly to said carrier. 110

6. An improved expansive and contractive deep well drill comprising a carrier, cutters 115 pivoted thereto, racks having connection with said cutters, a controlling bar movable through said carrier and having a shoulder, a cross bar connected to said racks and arranged in the path of travel of said shoulder, locking pawls pivoted to said racks and arranged in the path of travel of said shoulders and operated thereby, said locking pawls being adapted for locking engagement with the carrier, a holding dog pivotally supported by said carrier, a lug carried by said controlling bar and engaged with said dog whereby the weight of said 120 carrier is transmitted directly to said carrier. 125

trolling bar is transmitted directly to said carrier, and an operating lug rigidly connected to said rack and adapted to engage said dog to move the same from beneath said 5 first named lug.

7. An improved expansive and contractive deep well drill comprising a carrier, cutters pivoted thereto, racks having connection with said cutters, a controlling bar movable 10 through said carrier and having a shoulder, a cross bar connected to said racks and arranged in the path of travel of said shoulder, locking pawls pivoted to said racks and arranged in the path of travel of said shoulders 15 and operated thereby, a holding dog pivotally supported by said carrier, a lug carried by said controlling bar and engaged with said dog, an operating lug rigidly connected to said rack and adapted to engage said dog 20 to move the same from beneath said first named lug, and a combined holding and return lug connected to the racks and engaged with the intermediate portion of said dog.

8. An improved expansive and contractive 25 deep well drill comprising a carrier, cutters pivoted thereto, racks having connection with said cutters, a controlling bar having a shoulder, a cross bar connected to said racks and arranged in the path of travel of said shoulder, locking pawls pivoted to said racks 30 and arranged in the path of travel of said shoulder and operated thereby, a holding dog pivotally supported by said carrier, a lug carried by said controlling bar engaged 35 with said dog whereby the weight of said controlling bar is transmitted directly to said carrier, an operating lug rigidly connected to said rack and adapted to engage said dog to move the same from beneath said 40 first named lug, and a pin pivotally connecting said dog to said carrier, said controlling bar being provided with a slot slidably receiving said pin, said slot and said pin constituting a means to limit the sliding 45 movement of the controlling bar with relation to the racks and also to limit the upward movement of the racks with relation to the said carrier so that the tendency of the 50 cutters to expand by weight of the racks will at all times be preserved.

9. An improved expansive and contractive deep well drill comprising a carrier, bits pivoted thereto, links pivoted to said bits, racks pivoted to said links, a controlling bar having its lower end provided with a locking member, said links and said cutters being provided with registering grooves adapted 55 to receive said locking member.

10. An improved expansive and contractive deep well drill comprising a carrier, bits pivotally associated therewith, links connected to said bits and having their opposed sides formed with grooves adapted to be positioned directly opposite each other, and a controlling bar adapted to enter said op-

positely located grooves to lock the links and the bits connected thereto against accidental collapsing.

11. An improved expansive and contractive deep well drill comprising a carrier, bits pivotally associated therewith, links connected to said bits and having their opposed sides formed with grooves adapted to be positioned directly opposite each other, a controlling bar adapted to enter said oppositely located grooves to lock the links and the bits connected thereto against accidental collapsing, and racks movable longitudinally of said carrier and having connection with said links for controlling the same. 70 75 80

12. An improved expansive and contractive deep well bit comprising a plurality of cutters having their opposed sides formed with grooves, a controlling member adapted to be received in said grooves whereby to hold the cutters in a set position against the pressure thereon, and links connected to said cutters and having grooves registering with said first named grooves and adapted for the reception of said controlling member where- 85 90 95

by the links are held in a set position. 100

13. An improved expansive and contractive deep well bit comprising a plurality of cutters having their opposed sides formed with grooves, a controlling member adapted to be received in said grooves whereby to hold the cutters in a set position against the pressure thereon, links connected to said cutters and having grooves registering with said first named grooves and adapted for the reception of said controlling member where- 105 110 115

by the links are held in a set position, and racks connected to said links and having connection with said controlling member. 120

14. An improved expansive and contractive deep well bit comprising a carrier, cutters pivotally associated with said carrier, links pivoted to said cutters, racks connected to said links, and a controlling bar movable between said racks and having means to engage said links and said cutters for holding the same in a set position against the pressure on the cutters. 125

15. An improved expansive and contractive deep well drill comprising a carrier, cutters associated therewith, racks connected with said cutters for expanding and contracting said cutters, a controlling bar movable through said carrier between and in movable connection with the racks and having means to hold the cutters in expanded position, there being a pin and slot connection between the controlling bar and the carrier whereby to limit the movement of the controlling bar with relation to the carrier, and also to limit the upward movement of the racks with relation to the carrier and thus preserve the tendency of the cutters to at all times expand. 130

16. An improved expansive and contrac-

- 5 tive deep well drill comprising cutters, racks to which said cutters are pivotally connected for expanding and contracting the cutters, a controlling bar arranged between said racks and normally controlling movement thereof, and a plurality of weights mounted on said controlling bar and adapted for actuating said racks.
- 10 17. An improved expansive and contractive deep well drill comprising cutters, racks to which said cutters are pivotally connected for expanding and contracting the cutters, a controlling bar associated with said racks, a plurality of weights mounted on said controlling bar and adapted for actuating said racks, said controlling bar being provided with means holding the weights against downward movement on the controlling bar.
- 15 18. An improved expansive and contractive deep well drill comprising a controlling bar, cutters, means controlled by said bar for expanding and contracting the cutters, weights slideable on said bar, a gripping device carried by said bar, and a head on the bar having means operated by said weights for controlling said gripping device.
- 20 19. An improved expansive and contractive deep well drill comprising a controlling bar, gripping jaws carried thereby, a head movable on said controlling bar and having means to hold said jaws in engagement with a lowering mechanism, and weights movable on and normally controlled by said bar for shifting said head whereby to release the
- 25 jaws.
- 30 20. An improved expansive and contractive deep well drill comprising cutters, racks associated with the cutters, a controlling bar associated with the racks and extending a substantial distance upwardly from the racks, weights mounted on said controlling bar and adapted for forcing down said racks, gripping jaws associated with said controlling bar and having means for gripping a lowering mechanism, said jaws being provided with depending shanks, a head mounted on said controlling bar and having a groove to receive said shanks, a depending stem carried by said head and engaged by one of said weights, whereby to actuate said head.
- 35 21. An improved expansive and contractive deep well drill comprising cutters, racks supporting and controlling the cutters, a controlling bar connected with and controlling the racks, a gripping mechanism carried by said controlling bar and having depending shanks, a head mounted on said controlling bar and provided with means engaging said shanks whereby to hold the gripping mechanism in position, said head being provided with means to receive the shanks whereby to permit the gripping mechanism to move to its inoperative position, spring means urging said gripping
- 40 mechanism to its operative position and means mounted on and controlled by said bar for shifting the said head with respect to the said shanks.
- 45 22. An improved expansive and contractive deep well drill comprising a plurality of cutters, racks associated with the cutters, a controlling bar associated with the racks, sectional weights mounted on said controlling bar and adapted for actuating said racks, locking arms carried by a cross member at top of said racks and adapted to engage one of said weights whereby to limit the sliding movement of the same on said controlling bar, and a gripping mechanism associated with said controlling bar and operated by said weights.
- 50 23. An improved expansive and contractive deep well drill comprising a carrier, bits associated therewith, racks associated with the bits, a controlling bar adapted for engaging said bits to hold the same in position, weights mounted on said controlling bar, means to limit the sliding movement of one of the weights with relation to the controlling bar, a head having a pair of depending stems slideable through one of said weights and engaged by the other weight, a pair of jaws pivotally associated with the controlling bar and having depending shanks provided with inwardly directed terminal portions, said head being provided with an annular rib engaged with the inwardly directed terminal portion whereby to hold the jaws in their operative positions, said head also being provided with an annular groove to receive the inwardly directed terminal portions of said shanks, and spring means engaged with said shanks to urge the jaws to their operative positions.
- 55 24. An improved expansive and contractive deep well drill comprising a carrier, bits pivotally supported in connection therewith, links pivoted to said bits, racks movable with respect to the carrier and pivoted to said links, a controlling bar having its lower end provided with a locking member, said cutters being provided with registering grooves adapted to receive said locking members.
- 60 25. An improved expansive and contractive deep well drill comprising a plurality of cutters having their opposed sides formed with grooves, a controlling member adapted to be received in said grooves whereby to hold the cutters in a set position, links connected to said cutters, and racks connected to said links and having sliding connection with said controlling member, there being means to limit the sliding movement of the controlling member with relation to said racks.
- 65 26. An improved expansive and contractive deep well drill comprising a carrier, cutters pivotally associated with said car-

rier, links pivoted to said cutters, racks connected to said links and a controlling bar movable between said racks and having means to engage said cutters for holding the 5 same in a set position against the pressure in use on the cutters.

27. An improved expansive and contractive deep well drill comprising cutters, racks associated with the cutters, a control-

ling bar associated with the racks, a sectional weight mounted on said controlling bar and adapted to actuate said racks, hooked locking arms carried by said racks and adapted to engage said weight to limit sliding movement of the latter, and a gripping member associated with said controlling bar and controlled by said weight. 15

OSCAR MARTIN CARTER.
